SHEET DELIVERY MECHANISM FOR STOP-CYLINDER PRINTING MACHINES

Wilfred George Lawson and Frederick Stephen Jenkins, Chertsey, England, assignors, by mesne assignments, to Alfred Harry Lakeman, London, England

Application July 5, 1945, Serial No. 603,348
In Great Britain August 3, 1944

9 Claims. (Cl. 101—276)

1

The invention relates to improvements in the sheet delivery mechanism of a stop-cylinder printing press, that is, a press which has a reciprocating type bed and a cylinder to which a sheet of paper to be printed is fed as the cylinder is rotating and is printed during such rotation, the cylinder being stopped when the printing has been completed. It is during this stoppage of the cylinder that the sheet is removed from the printing cylinder by the delivery mechanism.

One object of the invention is to effect the lifting of the tail end of the printed sheet from the printing cylinder and to initiate the removal of the sheet by means of suction fingers or so-called suckers and to complete the removal of the sheet by means of a conveyor having mechanical grippers which take over the sheet presented to them and released by the suction fingers.

One important advantage of this co-operation of suction fingers and mechanical grippers is that the rapid and delicate raising and initiating the removal of the sheet can be effected by the suction fingers, whereas the completion of the removal of the sheet, comprising the major portion of the removal, can be efficiently effected by the stronger or more positive action of mechanical grippers. Moreover, the travel of the suction fingers need only be very short and the liability of a sheet being dropped by the fingers is reduced to a minimum. Further, as the conveyor can be provided with a plurality of sets of mechanical grippers for conveying the sheets away from the printing cylinder and depositing them on a piling table, the travel of the sheets so conveyed can be prolonged and thereby enable the sheets to dry and to prevent smearing or smudging of the printed matter and the necessity for interleaving.

Other objects are to improve the efficiency of the suction fingers in operation, to allow for and to facilitate adjustment of the operating mechanism of the suction fingers and of that of the conveyor to suit the length of sheet being printed, and preferably to ensure that when the driving mechanism of the suction fingers is adjusted, simultaneous corresponding adjustment of the conveyor is effected, thereby avoiding the necessity for the skill and time of the machine minder, which would be required if separate adjustments were required.

Further objects will be apparent from the following description of one example of sheet delivery mechanism according to the invention.

In the drawings:

Figures 1 and 1a together constitute a side elevation of a stop-cylinder press with one form of

the sheet delivery mechanism applied, only sufficient parts of the press being indicated to identify the machine, which is well known in the art.

Figure 2 is a rear sectional elevation taken on the line II—II, Figure 1.

Figures 3 and 4 are, respectively, a side elevation and a rear elevation showing the sucker bar, its valve box and other details on a larger scale than Figures 1 and 2, the printing cylinder being indicated in dot and dash lines.

Figures 5, 6 and 7 are side views of small levers which are to be mounted on the sucker bar and are herein shown separately for the sake of clearness.

Figure 8 is a side sectional elevation of the diaphragm motor for operating the smoothers.

Figure 9 is a side view of one of the suction fingers.

Figure 10 is a side elevation, partly in section, showing some of the parts in their relative positions, assumed when the suction fingers are giving up a sheet to the mechanical grippers on the conveyor.

Figures 11 and 12 are, respectively, a plan and a front view of one end portion of a gripper bar and its attachment to a chain.

Figures 13 and 14 are side views showing a cam and a gripper bar with its actuating lever in their relative positions when the mechanical grippers are opened and closed, respectively.

Figure 15 is a view of the rear end of the press showing the conveyor with its frame bars in section, the counter-balancing device for the frame bars and the piling table.

Referring first to Figures 1 and 2, the framework 1 of a stop-cylinder printing press supports a printing cylinder 2 on a shaft 3 mounted in bearings 4. As is well understood in the art, the printing cylinder is arrested at the end of a printing operation. The mechanism for driving the cylinder and effecting its arrest are not shown, as they are well known. Similarly the sheet feeding mechanism is omitted, the invention only being concerned with the sheet delivery mechanism which will now be described.

A tubular sucker bar 5, which is closed at its ends, is mounted to rotate or, more strictly, oscillate about its longitudinal axis in bearings 6 and 7. The bearing 6 is screwed to the upper end of a lever 8 and has an arm 9 provided with the bearing 1.

The lever 8 is mounted on a shaft 3' carried in bearings 192 forming part of a bracket 192, which is fixed to the frame 1. The shaft 3' is co-axial with the shaft 3 of the printing cylinder

2. The lever 8 is oscillated by a cam 10 which is clamped on a driving shaft 11 by a screw 12, as it has to be adjusted or set thereon for a purpose hereinafter explained. The shaft 11 is driven from the main shaft 120, through gear wheels 121, 122 fixed, respectively, on the shafts 120 and 11.

The cam 10 engages with a roller 13 on a lever 14 fulcrumed at 15 and linked by a rod 16 to a lever 17 which is freely mounted to oscillate on the shaft 3'.

The lever 17 has a head 18, Figure 3, for engagement with a flange 18' on the lever 8. The lever 17 is not connected to the lever 8 and makes a constant oscillation. The lever 17, however, makes contact with and thrusts the lever 8 in a direction towards the right hand, as considered with reference to Figure 1, and for convenience is hereinafter termed a contact lever.

A spring 19 is anchored at 197 and is attached by a cable 198 to the lever 8. When the contact lever 17 recedes, it allows the lever 8 to be returned by a spring 19, Figures 3 and 4, until arrested by a stop 191, Figure 10, which is clamped to an arcuate bracket 192 on the frame of the press. It is clamped by a screw 193 passing through an arcuate slot 194, so that it can be set in a position required to suit the length of the sheet being printed. The stop 191 determines the initial position of the lever 8 and will be referred to later on.

The sucker bar 5 is fitted with a number of hollow suction fingers 22 having rubber sucker pads 23 for engagement with the tail end of a printed sheet on the printing cylinder each time the cylinder stops. The sucker bar 5 extends along the cylinder 2 and the suction fingers 22 are fitted at suitable intervals. Each suction finger 22 preferably has a split boss 24, Figure 9, embracing the sucker bar 5 and tightened by a screw 25 when the boss is set on the sucker bar 5, so that a hole 26 in the suction bar coincides with the passage 27 of the suction finger. Each suction finger preferably has a cock 28 for controlling the passage 27.

In order to render the suction fingers 22 effective, air is withdrawn from the sucker bar 5 by any suitable means, such as an exhaust pump, not shown. The air passes out of the sucker bar 5 through a hole 29, Figure 4, passage 30, valve box 31 and pipe 32 which is connected to the exhaust pump. The valve box 31 is fitted with a slide valve 33 having a nipple 34, Figures 3 and 4, for the pipe 32.

The slide valve 33 has two rollers 35 and 36 for engagement, respectively, with a lever 37 and a cam or stop 38, Figure 1, so that it is reciprocated to open and to cut off suction, as required, by bringing the nipple into and out of coincidence with a suction hole 34', Figures 3 and 4, in the face of the valve box.

The valve box 31 is also fitted with a flap valve 39, Figure 4, pivoted on a pin 43 and controlling an air-inlet hole 40. The flap valve 39 is closed by a spring 41, Figure 3, surrounding a rod 42, one end of which embraces a pin 44 supported between lugs 45, 46 on the valve. The other end of the rod 42 slides in a lug 47 on the valve box. The lug 46 carries a roller 48 for engagement with a cam or stop 49, Figure 1, which is fixed on the framework of the machine. As hereinafter explained, when the roller 48 engages with the cam 49, the flap valve 39 is moved to uncover the air-inlet 40, so that air is admitted to the sucker bar 5.

A raising lever 50, Figure 3, has a split boss 51, Figure 6, which is clamped by a screw 52 to the sucker bar 5. The raising lever 50 has a rod 52' sliding in a lug 53 and surrounded by a spring 54 which tends to thrust the lever 50 upwards and so partly rotate the sucker bar 5 in one direction to raise the suction fingers 22. The boss 51 of the lever 50 has two projections 51', 52'' for engagement with the top of the lever 8, to limit the degree of oscillation of the sucker bar 5. A lowering lever 151 has a split boss 152, Figure 5, which is clamped to the sucker bar 5 by a screw 153. The lowering lever 151 has a roller 155 for engagement with a cam 156, Figures 3 and 4. The cam 156 is adjustably secured to a slotted spur wheel 157 by a screw 158. The spur wheel 157 is free to rotate on the shaft 3', which is co-axial with the shaft 3 of the printing cylinder 2 and meshes with a spur wheel 57', Figure 1, freely rotating on a stud 88 and fixed to a sprocket 87 driven by means of a chain 86 hereinafter referred to. The function of the cam 156 is to actuate the lowering lever 151 to rotate the sucker bar 5, against the action of the spring 54, when the printing cylinder stops, so that the suction fingers 22 are moved down with their pads 23 in contact with the tail end of the sheet on the printing cylinder, and will be referred to later in the description of the general operation of the delivery mechanism.

The lowering lever 151 has a second roller 60 for engagement with a stationary cam 61, Figures 2 and 10, mounted on the framework of the machine.

The cam 61 is shaped to ensure that the suction fingers 22 will be held in the correct position when presenting the sheet to the mechanical grippers of a conveyor hereinafter referred to. It is secured to the stationary part 192 by a screw 195 passing through a slot 196 in the cam, so as to allow for adjustment of the cam.

When smoothers are provided to engage with the printed sheet on the printing cylinder, it is desirable that they be rendered inoperative while the sheet is being removed from the cylinder. The smoothers 93, Figures 2 and 4, are carried by a shaft 94 (Figures 2, 4 and 8), mounted to oscillate in lugs 95 on collars 95' clamped to the sucker bar 5. A lever 96, clamped on the shaft 94, is pivotally connected to a rod 97 which is secured to a diaphragm 98, Figure 8, in a chamber 99. The part of the chamber above the diaphragm is in communication with the interior of the sucker bar 5 through passages 100, 101 and holes 102, 103. The part of the chamber 99 below the diaphragm 98 is open to the atmosphere through hole 105.

A spring 104 presses on the upper side of the diaphragm 98 and, when the interior of the sucker bar 5 is filled with air, the spring 104 holds the diaphragm down, so that the smoothers are pressed on to the sheet on the printing cylinder.

When the air is sucked out of the sucker bar 5, the pressure of the atmosphere on the underside of the diaphragm 98 overcomes the force of the spring 104, so that the rod 97 is pulled up and rocks the lever 96, to rotate the shaft 94, so that the smoothers 93 are raised to leave the sheet free to be removed from the printing cylinder 2 by the sucker fingers 22.

A stop disc 106 prevents the rod 97 rising too far.

The conveyor for taking the sheets from the suction fingers and for conveying them to the end 75 of the printing machine remote from the print-

ing cylinder and depositing them on the piling table, will now be described.

Two conveyor sprockets 62 are fixed on a forward conveyor shaft 63; Figure 1, and two conveyor sprockets 64 are fixed on a rear conveyor shaft 74, Figure 1a, both conveyor shafts being mounted in frame bars 75, so that they can rotate freely (Figures 1 and 15).

An endless chain 65 connects each pair of conveyor sprockets 62, 64.

The chains 65 carry gripper bars 66 at determined intervals. Each gripper bar is provided with a number of mechanical grippers, the number and spacing of the grippers corresponding to the number and spacing of the suction fingers. Each mechanical gripper consists of a pair of co-operating steel plates 67, 68.

The gripper plates 67 of each set of grippers for a gripper bar 66 are fixed to it. The corresponding movable gripper plates 68 are fixed to a shaft 69, mounted to rotate in the gripper bar 66, which is drilled to receive it. A pair of plates 70, 71 are fixed to the bar 66, and the shaft 69, near each end thereof, only one pair being shown in Figures 11 and 12. A spring 70 which is coiled about pins 71, closes the gripper plates 67, 68. A short lever 72, Figures 13 and 14, having a roller 72' is fixed to the shaft 69, near one end thereof. A cam 73 is mounted on the forward conveyor shaft 63 in a position to engage with the roller 72' as each gripper bar passes round the sprockets 62, and thereby to open the gripper plates 67, 68, carried by that gripper bar, so that they are ready to receive the tail end of a sheet presented to them by the suction fingers 22. As the rollers 72' leave the cam 73, the plates 67, 68 close on to the sheet and, as the gripper bar travels to the end of the machine, the sheets are conveyed thereto.

As each gripper bar 66 passes round the sprockets 64, its rollers engage with a stationary cam 74, Figures 1 and 15, so that the gripper plates 67, 68 are again opened against the influence of the closing springs 70, and the sheet carried by the gripper plates is released and allowed to fall on a piling table 72 which is fixed at this end of the machine.

The frame bars 75 are freely pivotally mounted at one end on a shaft 76 which is mounted in the framework of the machine and is the driving shaft of the conveyor. The frame bars 75 are supported at the rear end of the machine on struts 77. Each strut 77 is pivotally connected at 78 to its frame bar 75 and at 79 to a sleeve 79 sliding on a column 80. The sleeves 79 are connected to balance weights 82 by cords or chains 84 passing over pulleys 83, 83', 83''.

This arrangement allows the frame bars 75 and the chain conveyor to be raised sufficiently to enable the machine minder to get at the form and other parts of the printing machine.

The sprocket shaft 63 is driven indirectly from a sprocket 85 which is fixed to the cam 10, Figure 1, and therefore compelled to rotate therewith. A sprocket 81, spur gear 57 and a sprocket 89 are all fixed together but are free to rotate on the stud 88. A chain 86 connects the sprocket 85 to the sprocket 87. The sprocket 89 drives a chain 90 which, in turn, drives a sprocket 91 which is fixed on the shaft 76. A spur gear 92, fixed on the driving shaft 76 meshes with a spur gear 93 fixed on the forward conveyor shaft 63.

The chain conveyor is thus driven in synchronism with the cam 10, the number and spacing of the gripper bars being so arranged that each

time the cam 10 rotates and the suction fingers are moved over to the conveyor, a set of mechanical grippers, namely, co-operating gripper plates 67, 68, will arrive at the required position open and ready to receive a sheet presented to them by the suction fingers.

After each passing of a sheet, the suction fingers 22 return to their initial position. This position varies with the length of sheet to be printed, 10, so that the cam 10 has to be set accordingly, but, as the sprocket 85 is fixed to the cam 10, any adjustment of the cam 10 on its shaft automatically adjusts the conveyor chains 65. For example, the shorter the sheet the farther will the suction fingers 22 have to travel from the printing cylinder to the conveyor, so the cam 10 has to be set on its shaft 11 to suit and, in setting back the cam 10, so will the conveyor chains 65 be moved to set back the gripper bars. The cam 10 is adjusted by slackening the clamping screw 12 and rotating the cam relatively to the shaft 11. The initial position of the lever 8 and, therefore, the initial position of the suction fingers is determined by adjusting the stop 191, Figure 10.

It will be understood that before the cam 10 is re-set at any time, the cam 65 has to be set in the correct position on the slotted disc 57, to ensure that the sucker shaft will be partly rotated by the roller 55 and lever 151 to bring the suction fingers down on to the tail end of the sheet on the printing cylinder.

A brief description of the operation of the sheet delivery mechanism hereinbefore described will now be given.

Assuming that the cam 56, Figure 3, stop 191, Figure 10, and cam 10, Figure 1, have been set to suit a sheet of a certain length and that the parts are in the position indicated in Figure 3, a printed sheet will have been wrapped around the printing cylinder 2 and the cylinder will have stopped rotating. As the roller 55 has just moved to the highest part of the cam 56, the lever 151 has been raised to rotate partly the sucker bar 5 to bring the suction fingers 22 down with the sucker pads 23 pressed against the tail end of the sheet on the printing cylinder 2. At the same time, the lever 37 has been moved and pressed on the roller 35, to shift the slide valve 33 towards the right hand as seen in Figure 3, so that communication has been effected between the suction pipe 32 and the sucker bar 5 via the valve box 31, passage 30 and hole 29, Figure 4. Consequently, the sucker pads 23 of the suction fingers 22 take hold of the printed sheet. At the same time, the diaphragm 98, Figure 8, will have raised the smoothers 93. When the cam 10, Figure 1, has, through the medium of the roller 13, lever 14 and link rod 16, swung the contact lever 11 sufficiently to engage with the sucker bar lever 8, it swings the lever 8 towards the right hand, so that the suction fingers 22 carry the tail end of the sheet towards the conveyor. The final positions of the lever 8, sucker bar 5 and the suction fingers 22, when ready to give up the sheet, are indicated in Figure 10.

As these parts approach these positions, the rollers 36 and 48 engage with the stationary cams 38 and 49, Figure 1, respectively, so that the slide valve 33 and flap valve 39 are operated to cut off communication between the interior of the sucker bar 5 with the suction pipe 32 and open the sucker bar to the atmosphere.

As the lever 8 completes the above movement, the suction fingers 22 have placed the sheet in a set of open co-operating gripper plates 67, 68

which have just arrived to receive it. As the suction fingers release the sheet, the gripper plates 67, 68 close on to it and, as they move away, draw the sheet off the printing cylinder and carry it to the piling table.

The cams 74 open the gripper plates so that the sheet is deposited on the piling table.

When the suction fingers 22 have placed and released the tail end of the sheet in open gripper plates 67, 68, as above described, the cam 10, by means of the lever 14 and the rod 16, moves the contact lever 17 away from the lever 8, so that the lever 8 is returned to its initial position by its spring 19, and the suction fingers 22 are in position to move down on to the next sheet as the printing cylinder 2 completes its rotation and is stopped.

It will be appreciated that the travel of the suction fingers, while carrying a sheet to the mechanical grippers of the conveyor, is very short relatively to the travel of the sheet in the mechanical grippers on the conveyor.

The long travel on the conveyor gives ample time for the printing ink on the sheets to dry sufficiently, so that smudging of the printed ink is avoided.

Moreover, once the sheet has been gripped by the relatively more powerful or positive mechanical grippers, it can be pulled sufficiently off the printing cylinder.

We claim:

1. A sheet delivery mechanism for an underfed stop-cylinder printing press, having suction devices for engaging with the tail end of a printed sheet on the printing cylinder of the press when said suction devices are in initial position and for initiating the removal of the sheet from the printing cylinder, a conveyor having mechanical grippers for taking the sheet from the suction devices when the printing cycle has been completed and completing its removal from the printing cylinder and conveying it away therefrom, means for carrying the suction devices from their initial position to the conveyor and back to their initial position, and means for arresting said carrying means with their suction devices in their initial position, said arresting means being adjustable to regulate the initial position of the suction devices in accordance to the length of the sheet to be printed, whereby to regulate the movement of said suction device to effect engagement with the tail end of the printed sheet.

2. A sheet delivery mechanism for a stop-cylinder printing press, comprising suction fingers for engaging with the tail end of a printed sheet on the printing cylinder of the press and initiating the removal of the sheet therefrom, a sucker-bar carrying said suction fingers, a lever supporting said sucker-bar, said sucker-bar being mounted to oscillate on the lever and said lever being pivotally mounted on the shaft co-axial with that of the printing cylinder, a conveyor having mechanical grippers, means for oscillating said sucker-bar relatively to its supporting lever for the purpose of moving the suction fingers into and out of their operative positions, and means for moving the supporting lever towards the said conveyor to move the suction fingers towards the conveyor to allow the mechanical grippers thereof to take the sheet from the suction fingers to complete the removal of the sheet from the printing cylinder after the printing cycle has been completed, and means for arresting said lever in its initial position, said arresting means being

adjustable to determine said initial position to suit the length of sheet to be printed, whereby to effect engagement with the tail end of the printed sheet.

5. A sheet delivery mechanism for a stop-cylinder printing press according to claim 2, including a spring for returning the sucker-bar lever to its initial position after each operation, an adjustable stop for arresting the lever in its initial position on its return to suit the length of the sheet being printed, a contact lever for engaging with the sucker-bar lever and thrusting it against the action of the spring towards the conveyor, means including a cam for oscillating the contact lever, a shaft for the cam and means for adjustably fixing the cam on its shaft for the purpose of setting it on the shaft to suit the length of the sheet being printed.

4. A sheet delivery mechanism for a stop-cylinder printing press according to claim 2, including a spring for returning the sucker-bar lever to its initial position after each operation, an adjustable stop for arresting the lever in its initial position on its return to suit the length of the sheet being printed, a contact lever for engaging with the sucker-bar lever and thrusting it against the action of the spring towards the conveyor, means including a cam for oscillating the contact lever, a shaft for the cam, means for adjustably fixing the cam on its shaft for the purpose of setting it on its shaft to suit the length of sheet being printed, and a sprocket for driving the conveyor, said sprocket being fixed to the cam for the purpose of ensuring simultaneous adjustment of the cam and the sprocket.

5. A sheet delivery mechanism for a stop-cylinder printing press according to claim 2, said means for oscillating the sucker-bar relatively to the lever supporting it, for the purpose of lowering the suction fingers on to a sheet and of raising them to lift the sheet, comprising a wheel freely mounted on a shaft co-axial with the shaft of the printing cylinder, a cam adjustably secured to said wheel, means for rotating said wheel, a follower lever carried by the sucker-bar and having a roller engaging with said cam, and a raising lever on the sucker shaft and a return spring for actuating said raising lever.

6. A sheet delivery mechanism for a stop-cylinder printing press according to claim 2, said means for oscillating the sucker-bar relatively to the lever supporting it, for the purpose of lowering the suction fingers on to a sheet and of raising them to lift the sheet, comprising a wheel freely mounted on a shaft co-axial with the shaft of the printing cylinder, a cam adjustably secured to said wheel, means for rotating said wheel, a lowering lever carried by the sucker-bar and having a roller for engagement with said cam, and a raising lever on the sucker-bar and a return spring for actuating said raising lever, said lowering lever having means for controlling the suction fingers when presenting a sheet to the mechanical grippers of the conveyor, said controlling means consisting of a second roller on the aforesaid lowering lever, and a stationary cam for engagement with the second roller when the sucker-bar supporting lever is moved towards the conveyor.

7. A sheet delivery mechanism for a stop-cylinder printing press according to claim 2, said sucker-bar being provided with a suction valve and an air inlet valve, means being provided to open the suction valve and to close the air inlet valve when the suction fingers are to engage with

a sheet and to close the suction valve and open the air inlet valve when the suction fingers are to release a sheet.

8. A sheet delivery mechanism for a stop-cylinder printing press comprising suction fingers for engaging with the tail end of a printed sheet on the printing cylinder of the press and initiating the removal of the sheet therefrom, a sucker-bar carrying said suction fingers, an endless chain conveyor having mechanical grippers, means for moving said suction fingers relatively to the printing cylinder to engage with a sheet thereon, means for moving said sucker-bar, when the suction fingers are in engagement with a sheet, towards the conveyor to enable the suction fingers to present the sheet to the mechanical grippers thereof, and means for returning said sucker-bar and its suction fingers to their initial positions, a valve box on the sucker-bar having a suction valve and an air inlet valve, the suction valve consisting of a plate pivoted on the face of the box to control the suction opening and carrying a suction pipe nipple, means for moving said plate in one direction to uncover the suction opening and bring the nipple coincident therewith and means for closing the air valve when

15

10

5

the suction opening is uncovered, means for moving said plate to cover the suction opening and means for closing the air valve when the suction opening is uncovered by the plate, for the purposes hereinbefore set forth.

9. A sheet delivery mechanism for a stop-cylinder printing press according to claim 2, said sucker-bar carrying smoothers, and a diaphragm motor for raising and lowering said smoothers relatively to the printing cylinder whereby the smoothers are rendered inoperative when the suction fingers are in operative engagement with the sheet.

WILFRED GEORGE LAWSON.
